The ornamental design for a shoe midsole periphery, as shown and described.

DESCRIPTION

FIG. 1 is a top perspective view of a first embodiment of the shoe midsole periphery in accordance with our new design;

FIG. 2 is a front elevation view of a first embodiment of the shoe midsole periphery in accordance with our new design; FIG. 3 is a rear elevation view of a first embodiment of the shoe midsole periphery in accordance with our new design; FIG. 4 is a left side elevation view of a first embodiment of the shoe midsole periphery in accordance with our new design;

FIG. 5 is a right side elevation view of a first embodiment of the shoe midsole periphery in accordance with our new design;

FIG. 6 is a top plan view of a first embodiment of the shoe midsole periphery in accordance with our new design;

FIG. 7 is a bottom plan view of a first embodiment of the shoe midsole periphery in accordance with our new design;

FIG. 8 is a bottom perspective view of a first embodiment of the shoe midsole periphery in accordance with our new design;

FIG. 9 is top perspective view of a second embodiment of the shoe midsole periphery in accordance with our new design;

FIG. 10 is a front view of a second embodiment of the shoe midsole periphery in accordance with our new design;

FIG. 11 is a rear view of a second embodiment of the shoe midsole periphery in accordance with our new design;

FIG. 12 is a left side view of a second embodiment of the shoe midsole periphery in accordance with our new design;

FIG. 13 is a right side view of a second embodiment of the shoe midsole periphery in accordance with our new design;

FIG. 14 is a top view of a second embodiment of the shoe midsole periphery in accordance with our new design;

FIG. 15 is a bottom view of a second embodiment of the shoe midsole periphery in accordance with our new design; and,

FIG. 16 is a bottom perspective view of a second embodiment of the shoe midsole periphery in accordance with our new design.

The broken lines shown in the drawings represent portions of the shoe midsole periphery and environmental structure in the form of a shoe upper and outsole that form no part of the claimed design. The dashes immediately adjacent the claimed surface on either side near the toe define the bounds of the claimed design and form no part thereof.
